UNITED STATES PATENT OFFICE.

WILLIAM H. SAUVAGE, OF FLUSHING, NEW YORK, ASSIGNOR, BY MESNE ASSIGNMENTS, TO GOULD COUPLER COMPANY, OF NEW YORK, N. Y.

SLACK ADJUSTER.

1,411,872.

Specification of Letters Patent.

Patented Apr. 4, 1922.

Application filed September 25, 1918. Serial No. 255,670.

To all whom it may concern:

Be it known that I, WILLIAM H. SAUVAGE, a citizen of the United States of America, residing at Flushing, Long Island, in the 5 county of Queens and State of New York, have invented certain new and useful Improvements in Slack Adjusters, of which the following is a specification.

This invention relates to what is known 10 as railway slack adjusters and more particularly to automatic slack adjusters particularly designed for taking up the excess slack in the brake rigging of railway vehicles.

One of the objects of the present invention 15 is to provide a simple and practical automatic slack adjuster especially adaptable to the foundation brake rigging of railway cars, although with slight modification various features are applicable to other locations as well. Another object is to provide 20 a slack adjuster of the above general character adapted automatically to take up all of the slack on excess travel of brake rigging during a single application of the brakes in 25 contradistinction to devices now in use in which the slack is taken up on release of the brakes or only partially taken up on each application of the brakes. A further object 30 is to provide a mechanism of the last above mentioned character having relatively few parts which may be inexpensively manufactured, assembled and installed with the brake rigging now employed without extensive alterations and unnecessary trouble. A 35 further object is to provide a device of the last above mentioned character adapted to provide uniform piston travel at all times.

Other objects will be in part obvious from 40 the annexed drawings and in part indicated in connection therewith by the following analysis of this invention.

This invention accordingly consists in the features of construction, combination of parts and in the unique relations of the 45 members and in the relative proportioning and disposition thereof; all as more completely outlined herein.

Drawings depicting several desired forms 50 have been annexed as a part of this disclosure, and in such drawings, like characters of reference denote corresponding parts throughout all the views, of which—

Figure 1 is a plan view showing one of the 55 general arrangements of parts in normal position;

Figure 2 is an enlarged detail partial sectional view of substantially the parts of the mechanism shown in Fig. 1, a modified form of bypass being shown;

Figures 3 and 4 are views similar to Fig. 60 1 showing slight modifications capable of easy application to the brake rigging now in use;

Figure 5 is a detail sectional view of a modified cylinder.

Referring now to the drawings in detail, and more particularly to Figs. 1 and 2, a main power cylinder 10 of well known construction is positioned centrally beneath the car floor and comprises a piston head 11 and 65 piston rod 12, the latter being connected at one end 13 to a live lever 14 the opposite end 15 of which lever is connected by means of pull rod 16 with the brake rigging on one truck. At a point 17 about one-third of the 70 distance from the pivotal connection 13 of the piston rod is attached a pull rod or tie rod 18, the opposite end of which is connected at 20 to a cylinder or lead lever 21 at a distance slightly nearer to its center the 75 purpose of which will be hereinafter more 80 fully explained.

This cylinder lever 21 has one end 22 connected with a pull rod 23 extending to the other truck brake rigging at the opposite 85 end of the car, while the other end 24 of the cylinder lever 21 is trunnioned on opposite sides of a casing or housing 25 containing both temporary and permanent take up and holding mechanisms, hereinafter described 90 more in detail and shown in Fig. 2. The live lever 14 may be actuated by the hand brake mechanism operating through pull rod 26 and chain 27 connected therewith adjacent its point of connection 13 with the 95 piston rod of the power cylinder, if desired at any time. Both levers have their free or outer ends supported in U-shaped guides 28 suspended from the car floor.

This entire mechanism, broadly speaking, 100 is substantially the same as that now employed on railway cars, except that the end 24 of the cylinder lever is permanently connected to a relatively fixed or manually adjustable support instead of being connected 105 to the take up mechanism, as herein shown.

Referring now to Fig. 2, it will be seen that the main power cylinder 10 is provided with a supplemental or auxiliary cylinder 30 immediately in the rear thereof. This cyl- 110

inder is shown as a separate part but may be made integral as indicated in Fig. 5 and is provided with a piston 31 preferably slightly larger than the piston 11 in the main power cylinder 10 when the length of the arms of the live and dead levers is equal. The rear end of this auxiliary or slack adjuster cylinder 30 is connected by means of a by-pass 32 of any desired type 5 either as shown in Fig. 1 or formed in the cylinder wall, Fig. 2 with a port 33 in the main power cylinder 10 positioned according to the extent of piston travel desired. This is usually about six or seven inches 10 from the rear end 34 of the power cylinder or that adjacent the auxiliary cylinder. This wall is provided with an opening 35 at which point a triple valve (not shown) is connected for the purpose of controlling 15 the supply of air to and from the power cylinder in the usual manner.

The piston 31 is provided with a piston rod 36 extending through the end wall of the cylinder and into a suitable guide box 25 37, the free end of which rod is adapted to act against a compression return spring 38. closely adjacent and parallel to the piston rod 36 is a combined guide and adjusting rod 40 secured at one end in the end wall of 30 the auxiliary cylinder 30 and having its opposite end supported in the casing 37, the relative position of which may be adjusted by means of lock nut 41.

The housing 25 contains the permanent 35 and temporary take up and holding mechanisms and is preferably divided into two parts 42 and 43. The lower part 42, as shown in Fig. 2, or that adjacent the trunnion connection 24 with the dead lever 21 40 contains a plurality of dogs 44 each having an opening with case hardened edges through which the piston rod 36 is adapted to pass. These dogs are normally held in canted position by means of a spiral spring 45, as shown in Fig. 2 of the drawings. Other forms of holding means may be substituted, if desired, but it is found that these holding dogs provided with holes through which the piston rod passes are more satisfactory. 45

The upper part 43 of the casing 25 is also provided with a plurality of dogs 46 similar to those above described but occupying a relative vertical position, their ends being held in a tapered portion 47, Fig. 1, similar to that of the adjacent chamber and shown at the bottom of Fig. 2 and indicated at 48. These dogs are also held in canted position by means of a spiral spring 50 about the 50 stationary guide rod 40.

The operation of this mechanism is substantially as follows: When air is admitted into the cylinder 10 through the triple valve port 35 the main power piston 11 moves towards the left and the brakes are applied 60

through the live and dead levers in a well known manner. However, if the normal piston travel is exceeded, then the port 33 is uncovered by the rear edge of the piston 11 and air is admitted through the by-pass 32 70 to the auxiliary cylinder 30 to the back of the piston head 31. As this piston is slightly larger than the piston 11, it will move relatively towards the right under the same pressure together with the slack adjuster casing 75 25 to compress the spring 38 in the support 37, thus taking up all of the slack during the application of the brakes and insuring uniform piston travel at the same time. The casing 25 will slide freely along the guide 80 rod 40. When the air is exhausted out of the cylinders 10 and 30 to the atmosphere through the triple valve port, the pistons 11 and 31 through the action of the usual return springs go into full release position. 85 However, the two dogs 46 will grip the rod 40 and hold the casing or housing 25 relatively stationary in its newly adjusted position. The piston rod 36 is free to move towards the left through the dogs 44 under 90 the action of the release spring 38.

Fig. 1 shows the general arrangement of the brake rigging and attention is directed to the proportions previously stated and the slight difference in the dimensions of pistons 95 and points of connection of the rod 18 with the live and dead levers when the brakes are applied. Now should there be an excess movement of the piston 11 to exceed the pre-determined travel thereby uncovering the 100 port 33 and allowing the air to get into the slack adjuster piston chamber behind the piston 31, then owing to the greater leverage and power of this piston 31 and its connections with the dead lever the piston 11 will 105 be forced back towards the right until it again covers port 33, thus preventing any further air getting in behind the slack adjuster piston 31. In that event, piston 31 and rod 36 cease to move to the right. 110 When the brakes are released and the air exhausts to the atmosphere both pistons go to full release positions, and leave the slack adjuster casing 25 set to the right to the same extent that the piston 11 exceeded the 115 normal travel when the air pressure was in the cylinder. Thus any material excess travel of the main power piston is positively prevented at all times. This object may be accomplished in several ways, that is by having the pistons of the same size and the levers differently proportioned as shown in Fig. 1, or the pistons of different size and the levers differently proportioned as shown in Fig. 3. 120

On the next application of the brakes the piston 11 will probably not go beyond port 33 and no air will be admitted into the slack adjuster chamber until the brake shoes and wheels wear to an extent allowing the piston 130

11 to exceed its normal travel and again uncover the port 33. Under such circumstances, of course, this piston will be forced back to its predetermined travel by the 5 action of piston 31 and push rod 18 so that at no time in regular service will the piston 11 materially exceed its normal travel.

When it is desired to restore the slack adjuster to normal position after long use as 10 when replacing worn shoes, it is only necessary to release an unlocking handle 49 by movement towards the left. This handle moves in a slot 51 and aligns the three main holding dogs 44 on piston rod 36 and the 15 two adjusting rod dogs 46 in casing 25. That is, all the dogs will be moved to a right angle position with respect to the rods 36 and 40, thus unlocking the same and allowing the slack adjuster casing to go into 20 full release position. It is thus seen that on application of brakes, if the main piston exceeds its predetermined travel, it will automatically be adjusted while the brakes are being applied to the predetermined piston 25 travel.

The construction shown in Fig. 3, is substantially the same as that above indicated, except that it is perhaps more suitable to certain types of brake rigging now in general use. The slack adjuster mechanism is 30 separately mounted on a pair of independent brackets 52 and comprises a piston 53 of slightly larger diameter than the piston in the main power cylinder 10. The dead lever 35 21 is connected in substantially the same manner and proportions previously stated with a tie rod 18. The pull rod 23 connects one end with the truck brake rigging and the take up and holding mechanism is located in 40 a similar casing 25 at the opposite end where it is associated with the piston rod 54 of the piston 53. Adjacent the piston rod is a guide rod 55 with which the temporary take up and holding dogs coat. A return spring 45 56 acts directly on the piston 53. The operation of this device is about the same as that above described, and it is believed unnecessary to repeat.

The construction shown in Fig. 4 is in 50 principle substantially the same as that shown in Fig. 1 or Fig. 3. In this case the power cylinder 10 is of standard construction provided with the piston 12, the live and dead cylinder levers 14 and 21, the latter 55 of which is provided with a temporary and permanent take up and holding means within a casing 25, all as previously described. In this form as in Fig. 3, a separate auxiliary power cylinder 60 is connected with the 60 main power cylinder by by-pass 61. Both cylinders are secured to the under side of the car floor or framing and the piston 62 is provided with a yoke 63 extending thereabout and connected by means of rod 64 with the power cylinder 10. This rod 64 rests

loosely in a pocket 65 in the end wall of the cylinder 10 whereby it may have a relative movement with respect thereto. An adjusting rod 66 extends parallel to the rod 64 and the housing 25 is provided with temporary 70 and permanent take up and holding means similar to that shown in Fig. 2 adapted to coat with these rods.

In operation, if the normal piston stroke in the power cylinder 10 uncovers the port 75 leading to the by-pass 61 then air is admitted to the cylinder 60 which causes its piston 62 with yoke 63 to move relatively towards the right carrying the rod 64 and holding casing 25 therewith. Thus, taking up the 80 slack during the application of the brakes and insuring uniform piston travel and preventing material excess movement. When the brakes are released the holding dogs 85 coat with the adjusting rod 66 and cause a relative movement of the casing 25 within the rod 64 equal to the excess travel.

In Fig. 5, there is shown a modified form of cylinder 70 which is preferably made in one piece with the exception of the end walls 90 71 and 72. The main piston 73 travels in the right-hand portion, while an auxiliary piston 74 is housed in the left hand chamber. It will be noted that these chambers are separated by a dividing wall 75 provided 95 with a port 76 and a valve 77 adapted to normally close the port 76, except when the piston 73 exceeds its normal travel towards the right. A light spring 78 and the air pressure normally keeps the valve 77 closed, 100 but when its travel is such as to cause head 80 of valve stem 81 to coat with the base of the pocket in which the spring 78 is housed, then the valve 77 will be moved from its seat and allow air entering through the triple 105 valve port 82 to pass through the port 76 to operate the piston 74. These parts are of course connected in the manner shown in Figs. 1 and 2 and a further description of the operation is believed to be unnecessary. 110

From the above, it will be seen that the present mechanisms are particularly adapted for the foundation brake rigging of railway cars now in use and may be applied thereto without material alterations or unnecessary expense. These types of slack adjuster insure uniform piston travel under all circumstances and positively and definitely take up all the excess slack or false motion of the brake rigging during each 120 application of the brakes in contradistinction to the taking up of the slack as the brakes are released after the operation, thus making the mechanism as a whole more reliable and efficient.

Without further analysis, the foregoing will so fully reveal the gist of this invention that others can by applying current knowledge readily adapt it for various applications without omitting certain features that, 130

from the standpoint of the prior art, fairly constitute essential characteristics of the generic or specific aspects of this invention, and therefore such adaptations should and 5 are intended to be comprehended within the meaning and range of equivalency of the following claims.

I claim:

1. In an automatic slack adjuster, in combination, a source of compressed air, permanent take up and holding means, and means directly acted on by the air acting between the source of compressed air and the take up and holding means adapted to actuate the latter on application of the brakes to take up all of the slack on each application.
2. In an automatic slack adjuster in combination, a source of compressed air, a piston actuated thereby, permanent take up and holding means, and means acted on by the air and actuated on excess travel of the piston during the application of the brakes adapted to actuate said holding means to take up all of the slack on each application.
3. In an automatic slack adjuster, in combination, a power piston, permanent take up and holding means, and means directly acted on by the air acting between the power piston and the take up and holding means adapted to actuate the latter on application of the brakes to take up all of the slack, said last means including a cylinder having a piston of slightly larger diameter than the power piston.
4. In an automatic slack adjuster, in combination, a power cylinder, an auxiliary cylinder, pistons in said cylinders of different size, live and dead levers connected with said pistons respectively, and permanent take up and holding means directly acted on by the air associated with one of said levers adapted to be actuated on application of the power cylinder to take up all of the slack.
5. In an automatic slack adjuster, in combination, a power cylinder, an auxiliary cylinder, both having pistons, a by-pass connecting said cylinders adapted to transmit air from the power cylinder to the auxiliary cylinder when excess travel of the power piston takes place, and slack adjuster mechanism directly acted on by the air adapted to be actuated on operation of said auxiliary cylinder to take up all of the slack.
6. In an automatic slack adjuster, in combination, a power cylinder, an auxiliary cylinder, pistons and rods in said cylinders, live and dead levers connected with said piston rods respectively, take up and holding mechanism under the direct action of the air associated with one of said levers, and means whereby the auxiliary piston is moved to operate said take up and holding mechanism when said power piston exceeds its predetermined travel.
7. In an automatic slack adjuster, in combination, a power cylinder, an auxiliary cylinder, pistons and piston rods operatively associated therewith, live and dead levers connected with said piston rods respectively, a by-pass connecting said cylinders, a guide rod parallel to said auxiliary piston rod, permanent and temporary take up and holding mechanism on said piston rod and guide rod respectively forming a point of connection between the said piston rod and dead lever, whereby as said auxiliary piston is actuated on excess travel of the main piston by air passing through said by-pass, said temporary and permanent take up and holding mechanisms will be successively actuated to take up the slack.
8. In an automatic slack adjuster, in combination, a power cylinder, an auxiliary cylinder, pistons and piston rods operatively associated therewith, live and dead levers connected with said piston rods respectively, a by-pass connecting said cylinders, a guide rod parallel to said auxiliary piston rod, permanent and temporary take up and holding mechanism on said piston rod and guide rod respectively forming a point of connection between said auxiliary piston rod and dead lever whereby as said auxiliary piston is actuated on excess travel of the main piston said temporary and permanent take up and holding mechanisms will be successively actuated to take up the slack, and means for releasing the temporary and permanent take up and holding mechanisms whereby the parts may be restored to normal position when it is desired to apply the new brake shoes.
9. In an automatic slack adjuster, in combination, a power cylinder having a piston, an auxiliary cylinder and piston, a live lever connected to one, a dead lever connected to the other, a rod connecting the central parts of said levers, the connection of said rod with the dead lever being nearer to the center thereof than its connection with the other lever, and take up and holding means associated with one of said levers, operative on application of the brakes to take up all of the slack at each operation.
10. In an automatic slack adjuster, in combination, a power cylinder, a live lever, a dead lever, an auxiliary cylinder, pistons in said cylinders connected with the ends of said live and dead levers respectively, take up and holding means associated therewith and a rod acting between the central parts of said live and dead levers, the point of connection of said rod with the dead lever being nearer the center of the dead lever than the point of connection of said rod with the central part of the live lever.
11. In an automatic slack adjuster, in combination, a power cylinder, and an auxiliary cylinder, a live lever connected with one, a dead lever connected with the other, and a rod connecting the central parts of said levers,

take up and holding means associated therewith, the connection of said rod with the dead lever being nearer to the center than its connection with the other lever, pull rods 5 connected with the outer ends of said live and dead levers and a guide and stop member supporting said ends.

12. In an automatic slack adjuster, in combination, a power cylinder, an auxiliary cylinder of different size, a live lever connected to one cylinder, a dead lever connected to the other, a rod connecting the central parts of said levers, take up and holding means associated therewith, the connection of said 15 rod of the dead lever being nearer to the center than its connection with the other lever, and return springs for restoring both the live and dead levers to normal position.

13. In an automatic slack adjuster, in combination, a power cylinder, an auxiliary cylinder, pistons therein, and live and dead levers connected respectively with said pistons, and one of said points of connection including a housing having slack adjuster 25 mechanism contained therein.

14. In an automatic slack adjuster, in combination, a power cylinder, an auxiliary cylinder, pistons therein, and live and dead levers connected respectively with said pistons, and one of said points of connection including a housing having slack adjuster mechanism contained therein, said slack adjuster mechanism including permanent and temporary take up and holding means.

15. In an automatic slack adjuster, in combination, a power cylinder, an auxiliary cylinder, pistons therein, and live and dead levers connected respectively with said pistons, and one of said points of connection 30 including a housing having slack adjuster mechanism contained therein, said slack adjuster mechanism including permanent and temporary take up and holding means, and means for releasing said holding means 40 whereby the parts may be freely moved to any desired position.

16. In an automatic slack adjuster, in combination, a power cylinder, an auxiliary cylinder, pistons therein, live and dead levers 50 connected with said pistons, automatic slack adjuster mechanism associated with one of said pistons adjacent its point of connection with its respective lever, and a release spring acting on said piston adapted to aid in re- 55 storing the parts to normal position.

17. In an automatic slack adjuster, in com-

bination, a power cylinder, an auxiliary cylinder, pistons therein, live and dead levers associated with said pistons, slack adjuster holding mechanism associated with one of 60 said levers adapted to be actuated on excess travel of the power piston to take up all of the slack, and means actuated on any excess travel for preventing material excess travel of said power piston.

18. In an automatic slack adjuster, in combination, a power cylinder, an auxiliary cylinder, pistons therein, live and dead levers associated with said pistons, slack adjuster mechanism associated with one of said levers 65 adapted to be actuated on excess travel of the power piston to take up all of the slack, and means for limiting the main piston to substantially its normal piston travel regardless of the slack to be taken up.

19. In an automatic slack adjuster, in combination, a power cylinder, an auxiliary cylinder, a by-pass connecting said cylinders, pistons in said cylinders, live and dead levers connected with said pistons respectively 70 whereby when said main piston exceeds its predetermined travel, the air in said cylinder will escape through said by-pass to the auxiliary cylinder to actuate the other piston, said live and dead levers being so proportionately connected as to cause said power piston to again cover the port of the by-pass whereby all of the slack in the brake rigging 75 is taken up by actuation of the auxiliary piston.

20. In an automatic slack adjuster, in combination, a double end brake cylinder and brake rigging, a source of pressure applicable at both ends, two pistons, and means associated with said pistons whereby a uniform stroke is automatically obtained while 80 the brake is being applied to take up all of the slack.

21. In a slack adjuster, in combination, a two-part brake cylinder, a power piston and take up piston therein and brake rigging, a source of pressure, means whereby a substantially uniform stroke of the power piston is automatically obtained at all times, means adapted to take up all of the slack at each 100 operation of said power piston, and means actuated by the other piston adapted to prevent a material excess travel of the power piston.

In testimony whereof I affix my signature. 110

WILLIAM H. SAUVAGE.
